UNITED STATES PATENT OFFICE

ABRAHAM ESAU, OF JENA, GERMANY

SHORT-WAVE OSCILLATOR

Application filed October 25, 1927, Serial No. 228,526, and in Germany October 29, 1926.

The present invention relates to the generation of short electric waves by means of a spark oscillator. Whilst formerly very short waves of the damped kind were generated by means of spark gaps, at the present time thermionic valves are used almost exclusively; these, as is well known, enable undamped oscillations to be produced, such as have gradually come more and more to 10 the front during the development of the wireless industry.

The present invention provides a means for producing waves which are practically as little damped as possible, with the use of 15 a spark gap, this method, compared with production by means of valves, having a number of advantages, more particularly when it is a question of the generation of very short waves for large amounts of energy and of 20 good modulation.

As is well known, the output obtained in a spark transmitter can be expressed by the formula $W = \frac{1}{2}zCV^2$, in which z is the number of sparks per second, C the capacity of 25 the circuit and V the voltage across the condenser at the beginning of the discharge. An increase of capacity for the purpose of obtaining greater energy output, when it is a 30 question of the generation of short waves, may be at once eliminated, as the wave length varies with the capacity and the latter must be therefore kept as low as possible. A limit is also soon set to an increase of voltage and the consequently required increase of the 35 spark gap or of the number of spark gaps firstly because for practical reasons the voltage can be raised only up to a certain point and further because the electric inherent dimensions of the circuit increase with the 40 increase of the spark gap, and this will again affect the wave length, respecting which the circuit dimensions are of paramount importance, more particularly in the case of very short waves; thus, an increase of energy 45 cannot be obtained in that manner. As will be seen from the formula, there remains only the possibility of increase in the number of sparks per second z . A process has been already proposed in which two spark gaps are 50 connected in cascade and in which the damped

oscillations generated by the first spark gap are used for working the second spark gap. The oscillations thus obtained are damped, in the same way as when a single spark gap is used, for the currents feeding the second spark gaps are already constituted by damped alternating current trains succeeding each other. It has also been proposed to supply spark gaps with low or medium frequency alternating current up to 2000 periods per second, for the purpose of obtaining an audible sound in a receiver, that is to say intentionally a damped oscillation. 55 60

According to the present invention a circuit including a spark gap is supplied with alternating current of a frequency higher than that of audition, whereby the wave trains generated and following each other, although individually damped, produce a practically undamped oscillation. It is preferable 65 to dimension the spark gap in such a manner that at each half period of the supply high frequency current, a spark shall pass, producing a corresponding impulse in the oscillation circuit. 70 75

For the purpose of generating the alternating current any device known per se can be used, such as high frequency alternating current machines which as a rule give frequencies of about 8000-15000, or voltaic arcs or 80 valve generators, etc. Further, in the present state of the wireless industry, there is no difficulty in arranging quenched spark gaps with an action practically sufficient for 85 quenching such high spark frequencies as are in question.

The invention will now be explained more fully with reference to the accompanying drawing, which illustrates one manner of carrying it into effect, and in which: 90

Figure 1 is a diagrammatic view of an oscillation system for carrying my invention into practical effect.

Figure 2 is a view showing unmodulated and modulated voltages. 95

Referring to Figure 1, I is the high frequency generating circuit, constituted in the present case by a three electrode valve in "oscillation generating connection"; for this purpose also a high frequency machine could 100

be used. II is the spark gap circuit and III a work or radiation (aerial) circuit. r is the valve, L^1 , C^1 are respectively the valve oscillation circuit inductance and oscillation circuit capacity, L^2 is a coupling coil for coupling to the spark gap F. C^2 and L^3 constitute the oscillation circuit excited intermittently by the spark gap; the constants of this circuit, when it is a question of generation of very short waves (of the order of value of a few meters or centimeters), can be determined by the geometrical dimensions. L^4 is the coupling coil of the aerial A, and E the point of connection for the earth conductor.

15 An advantage of the invention is that it is possible to effect in a simple manner a modulation of the waves radiated, for, as is well known, such modulation in the case of short waves offers in practice with present 20 systems great difficulties owing to the inconstancy of the wave lengths when using valve generators. For that reason, according to the invention, the high frequency current used for charging the spark gap is modulated 25 rather than the oscillations generated (i. e. in Figure 1 the oscillations in the aerial circuit A, L^4 , E); this is effected by an inserted modulation device of a kind well known in itself, marked M in Figure 1, for example, a 30 microphone or its equivalent. It is an essential condition that the modulation should take place in such a manner that at least the effective voltage for the spark gap shall be still retained even in the case of the strongest 35 modulation. This is more fully shown in Figure 2, in which a indicates the unmodulated high frequency voltage for the spark gap, b the corresponding modulated voltage V, whilst V_E is the voltage required to produce 40 sparking, that is the minimum voltage, in the case of the strongest modulation, which must be produced.

The invention offers particularly great advantages when applied to the generation of 45 very short waves, not exceeding 1 meter, where a direct generation, for instance by means of valves, presents great difficulties. In practice, a valve will be utilized for generating the shortest wave which can be adequately generated, and further reduction will be effected by the connection to a spark gap, owing to which it will become possible to produce waves of the shortest wave lengths such as have been hitherto unattained.

55 What I claim is:

1. A short wave oscillator comprising a vacuum tube generator for producing undamped high frequency oscillations in a 60 range above audibility range, a spark gap circuit for raising said undamped high frequency oscillations to a frequency higher than their generated frequency, and a work circuit on which the resulting individually damped successive oscillations are impressed

so as to produce a practically undamped wave.

2. A short wave oscillator comprising means for producing undamped high frequency oscillations in a range above audibility range, a spark gap circuit for raising said undamped high frequency oscillations to a frequency above their generated frequency, a work circuit on which the resulting successive individually damped oscillations are 75 impressed so as to produce a practically undamped wave, and means for modulating said undamped high frequency currents supplied to the spark gap in accordance with signals to be transmitted.

In testimony whereof I have affixed my signature.

ABRAHAM ESAU.
